UNITED STATES PATENT OFFICE

LEONARD FRIEDBERG, OF NEW YORK, N. Y., ASSIGNOR TO FURLAGER MANUFACTURING COMPANY, INC., OF NEW YORK, N. Y., A CORPORATION OF NEW YORK

VANITY CASE

Application filed November 8, 1930. Serial No. 494,411.

The invention has for an object to provide a vanity case with two compartments in which may be disposed a powder puff and a rouge puff respectively.

5 Another object of the invention is to provide the vanity case with an opening for one of the compartments through an edge of the vanity case and an opening for the other compartment through a face of the vanity case, means being provided for closing the two openings.

A further object of the invention is to separate one of the compartments by gauze at one side of which a supply of powder may 15 be disposed, the powder puff being disposed at the other side of the gauze.

Still another object of the invention is to provide a vanity case having a compartment which may be reached through an opening in the edge of the vanity case, the compartment being divided by gauze, the compartment at one side of the gauze being accessible through an opening in the vanity case in which a powder puff may be disposed, the vanity case 20 at the other side of the gauze serving as a receptacle for powder which may be supplied through an opening in a face of the vanity case which is normally closed by a box member provided with a lid and in which is normally disposed a rouge puff.

Additional objects of the invention will appear in the following specification in which the preferred form of the invention is described.

35 In the drawings similar reference characters refer to similar parts in all the views, of which

Figure 1 is a side view of the vanity case, parts being broken away to illustrate the construction.

Figure 2 is a sectional view on the line 2-2 of Figure 1, and

Figure 3 is a sectional view similar to the view illustrated in Figure 2, but with the parts shown in a different position.

By referring to the drawings it will be seen that the vanity case has a hollow body 5 which is preferably manufactured of a flexible material having face members 6 and 50 7 which are open at the end 8 and which are

secured together at the sides 9 and the bottom 10 of the vanity case, the face members 6 and 7 having frame members 11 and 12 respectively at the opening 8 in the vanity case, these frame members 11 and 12 being pivoted at 13 in a manner readily understood. The frame members 11 and 12 are provided with fastening means, as, for instance, the plate 14 which extends from the frame member 11 and provided with an opening 15 in which a latch member 16 extending from the frame member 12 is normally disposed. This plate member 14 may also have a slot 17 by means of which it may be secured or attached to a ribbon, chain or other member.

The face member 7 has an opening 18 and there is disposed in this opening 18 an open frame 19, the open frame 19 having flanges 20 and 21 for embracing the face member 7 and an inner member 22 at the opening 18 in the face member. This inner member 22 preferably extends to the opening 18 where it is embraced by the frame member 12.

The open frame 19 has an inwardly extending enclosing wall 23 and extending against the inner side of the enclosing wall 23 there is a gauze member 24 which serves to form a compartment 25 in the hollow body 5, the outer wall of this compartment 25 being a box member 26 which is normally disposed for closing the opening in the open frame 19.

The box member 26 serves as a receptacle for a rouge cake 27 and a rouge puff 28, the box member 26 being normally closed by a lid 29 having a mirror 30 at its inner face. The flange 20 of the open frame 19 has two hinge knuckles 31, the box member 26 has two hinge knuckles 32 and the lid 29 has a hinge knuckle 33, a pin 34 being disposed through these several hinge knuckles so that the box member 26, as well as the lid 29, will be hinged to the open frame 19.

In the hollow body 5 between the face member 6 and the gauze member 24 there is disposed a powder puff 35 which may be reached through the opening 8 in the hollow body 5, powder reaching the powder puff 35 through the gauze member 24, which is filled

through the open frame 19 when the box member 26 is moved outwardly therefrom by means of its flange 36. When the box member 26 is in normal position, as illustrated in the drawings, the powder will pass through the gauze member 24 to the powder puff 35, as has been stated, while the rouge puff may be reached by raising the lid 29 of the box member 26, as illustrated in the full lines in Figure 2. When the lid 29 has been raised, as stated, the mirror 30 at the inner face of the lid 29 may be used to apply the rouge and powder.

What is claimed is:

1. A vanity case having a hollow body, a gauze member for dividing the body into two compartments, the body having two openings for reaching the compartments respectively, a box member for closing one of the openings, the other opening serving to permit of the introduction of a powder puff into a compartment, a lid for closing the box member, and means for closing the said other opening.

2. A vanity case with a hollow body having a face and an edge, the body having an opening in its edge through which a powder puff may be introduced and another opening in its face, a gauze member for dividing the body into two compartments, which may be reached through the openings respectively, a box member for closing the opening in the face of the body, a lid for closing the box member, and means for closing the opening in the edge of the body.

3. A vanity case with a hollow body having a face and an edge, the body having an opening in its edge through which a powder puff may be introduced and another opening in its face, a gauze member for dividing the body into two compartments, which may be reached through the openings respectively, the compartment between the gauze member and the opening in the face of the hollow body serving to hold a supply of powder and the other compartment serving to hold a powder puff, a box member in which a rouge puff is normally disposed for closing the opening in the face of the body, a lid for closing the box member, means for closing the opening in the edge of the body.

4. A vanity case having a hollow body with two openings leading to the interior of the hollow body, a box member, a lid for the box member, the box member and the lid being hingedly connected to the body at one of the openings for closing the said opening, the other opening serving to permit of the introduction of a powder puff, and a gauze member for separating the hollow body into two compartments adjacent the last mentioned opening.

5. A vanity case having a body with an opening, an open frame secured to the body at the opening and provided with an inward-

ly enclosing wall to form a compartment, a box member normally disposed in the outer portion of the open frame to close the compartment in the latter, a lid for closing the box member, the box member and the lid being hingedly connected to the open frame.

6. A vanity case having a body with an opening, an open frame secured to the body at the opening and provided with an inwardly enclosing wall to form a compartment, a box member normally disposed in the outer portion of the open frame to close the compartment in the latter, a lid for closing the box member, the box member and the lid being hingedly connected to the open frame, and a gauze member disposed at the inner side of the enclosing wall.

7. A vanity case having a body with an opening, an open frame secured to the body at the opening and provided with an inwardly enclosing wall to form a compartment, a box member normally disposed in the open frame to close the latter, a lid for closing the box member, a gauze member disposed at the inner side of the enclosing wall.

8. A vanity case having a hollow body with openings leading to the interior of the hollow body, a box member having a hinged knuckle, a lid for closing the box member, the lid having a hinged knuckle in alignment with the first hinged knuckle, the box member being disposed at one of the openings in the hollow body, and a pin secured to the hollow body at the last mentioned opening and engaging the hinged knuckles.

9. A vanity case having a hollow body, a gauze member dividing the hollow body into two compartments, the body having an opening in its edge through which a powder puff may be introduced into one of the compartments and another opening in its face through which powder may be introduced into the other compartment, a box member for closing the opening in the face of the body, a lid for closing the box member, and means for closing the opening in the edge of the body.

10. A vanity case with a hollow body having opposite face members secured together at their sides and bottom, the hollow body having an opening at the upper edges of the face members through which a powder puff may be introduced, there being an opening in one of the face members, an open frame secured in the second mentioned opening, a gauze member at the inner portion of the open frame to separate the interior of the open frame from the interior of the hollow body in which the powder puff is normally disposed, a box member for closing the outer portion of the hollow frame, and a lid for the box member.
